SUPPORTING APPARATUS

William E. Schmidt, Northside, Pa., assignor to
C. K. Manufacturing Company, Inc., Pittsburgh,
Pa., a corporation of Pennsylvania

Application March 2, 1938, Serial No. 193,391

4 Claims. (Cl. 285—1)

My invention relates to fastening apparatus and has particular relation to apparatus incorporating a tube which is to be securely mounted in a frame and to the ends of which torques are to be applied.

The present application constitutes an improvement of application for Electro-chemical apparatus, Serial No. 173,603, filed November 9, 1937, to George A. Hazen, and assigned, by mesne assignments, to the C. K. Manufacturing Company.

The above-mentioned application is directed to a cleaning system for colloidal suspensions, in which the cleaning takes place in a tube mechanically coupled to a coil system through which the colloidal liquid flows. The tube is mounted in a container and a potential is supplied to the liquid in the container through a terminal projecting laterally from the tube. I have found, in mounting the tube in the container in a manner taught by the prior art of which I am aware, that when the tube is coupled to the supply coil and is subjected to a torque applied in tightening the coupling, it turns about its axis to a considerable extent. By the turning the lateral terminal is displaced and the electrical connection is broken or otherwise deleteriously affected.

It is, accordingly, an object of my invention to provide a mounting arrangement for a tubular element that shall prevent its turning about its axis when it is subjected to torques.

Another object of my invention is to provide a simple and inexpensive mounting for a tubular element which, when used, shall prevent the turning of the tubular element about its axis when torques of substantial magnitude are applied anywhere to the tubular element.

More specifically stated, it is an object of my invention to provide a contrivance for mounting a tubular element in a container in such manner that when the tubular element is subjected to torques, its position as regards its longitudinal axis shall not change.

According to my invention, I provide a collar which is secured to the tubular element by welding, soldering or sweating. The external sides of the collar are of such geometric structure that they engage the walls of the container when the tubular element is in position. Torques applied to the tubular element are counteracted by the engagement of the collar with a wall of the container and the tubular element is thus prevented from turning.

The novel features that I consider characteristic of my invention are set forth with particu-

larity in the appended claims. The invention itself, however, both as to its organization and its method of operation, together with additional objects and advantages thereof, will best be understood from the following description of a specific embodiment when read in connection with the accompanying drawing, in which

Figure 1 is a view in top plan showing a preferred embodiment of my invention;

Fig. 2 is an enlarged view in section taken along line II—II of Fig. 1, and

Fig. 3 is an enlarged view in section taken along line III—III of Fig. 2.

The specific structure and the detailed functioning of the complete system involved in the present application will be found in the above-mentioned Hazen application, and except for the specific features involved in the present invention, will be discussed only lightly here. For a more detailed discussion, reference is made to the said Hazen application.

The apparatus comprises, in general, one or more tubular elements 5, each of which is coupled at its ends to the coil 7 through which the colloidal liquid subjected to the treatment passes. Specifically, the Hazen invention applies to the treatment of malt liquids, such as beer, and in this case, the tubular element 5 is attached to the beer coil 7 extending from the beer barrel (not shown) to the spigot (not shown) at the dispensing bar. The tubes 5 are mounted in a suitable rectangular container 9 and extend through openings 11 in the side walls 13 of the container. The coupling to the coil 7 takes place outside of the container 9 and adjacent to the side walls 13.

The coupling devices 15 used are described in detail in the above-mentioned Hazen application. Each device includes a hexagonal tightening nut 17 which is screwed on to the threaded ends 19 and 21 of the tubular element 5 fastening the terminals of the coil 7 to the tubular element in such manner that no leakage of the malt liquid takes place.

Within the tube 5, a metallic strand (not shown here) for applying a potential to the liquid is provided, as described in the Hazen application. The strand is connected to one output tap 23 of a supply transformer 25 through an insulated terminal 27 projecting laterally from the tubular element 5. The other output tap 29 of the transformer is grounded to the container wall 13 and thus a difference of potential is impressed on the liquid flowing through the tube 5.

In the apparatus constructed in accordance

with the teaching of the prior art, the tubular element 5 turned on its longitudinal axis when the nuts 17 at the ends were tightened and carried with it the projecting terminal 27 breaking 5 the connection between the terminal and the transformer 25. In accordance with my invention, the turning is prevented by securing near one end 21 of the tubular element 5, a collar 31 having a threaded circular hole 32 and external 10 sides 33 and 35 forming a rectangle. The threads at the other end 19 of the tube 5 extend for a substantial distance and the tube 5 is slipped into the openings 11 in the side walls 13 in such manner that the collar rests against the right hand side-wall. The collar 31 is of such dimensions that one of its sides 33 engages the front or the rear wall 37 of the container 9 adjacent to the tubular element 5 and another side 35, which extends along the top of the container 9, engages 15 a cover 39 which is, in the practice of my invention, secured to the container. When the nuts 17 at the end of the tubular element 5 are now tightened, the sides 33 and 35 of the collar press against the wall 37 and the cover 39 of the container and prevent the tubular element from 20 turning on its axis.

Of course to withstand the torque applied, the collar 31 should be rigidly secured to the tube 5. Where the torque will always be relatively small, the collar 31 may be fastened simply by welding or soldering. However, in general, the torque applied may be large, and it is, therefore, desirable that the collar 31 be sealed to the tube 5 by sweating. The sweating process used in the practice of my invention comprises first engaging the threads in the hole 32 of the collar 31 with those in the end 21 of the tube. A suitable acid flux is then applied to the junction of the collar 31 and the tube 5, and then the tube 5 is heated by a blow 30 torch in the region of the collar and solder is applied to the junction. The solder flows into the junction region between the threads of the collar and the threads on the tube, completely filling this region. When the solder subsequently forms a hardened layer 41, the collar 31 is tightly sealed to the tube 5.

Although I have shown and described a certain specific embodiment of my invention, I am fully aware that many modifications thereof are pos-

sible. My invention, therefore, is not to be restricted except insofar as is necessitated by the prior art and by the spirit of the appended claims.

I claim as my invention:

1. In combination, a frame having a longitudinal wall portion and transverse wall portions, a tubular element extending through said transverse wall portions adjacent to said longitudinal wall portion and means secured to said tubular element and adapted to engage said longitudinal wall portion to prevent said tubular element from turning when a torque is applied thereto. 5

2. In combination, a frame comprising a longitudinal wall portion having a plane surface and transverse wall portions, a tubular element 15 extending through said transverse wall portions adjacent to said longitudinal wall portion and a collar having external sides forming a rectangle secured to said tubular element in a position such that one of the sides of the collar substantially 20 engages said plane wall surface to prevent said tubular element from turning when a torque is applied thereto.

3. In combination, a frame comprising a longitudinal wall portion having a plane surface and 25 transverse wall portions, a tubular element threaded at one end extending through said transverse wall portions adjacent to said longitudinal wall portion and a collar having external sides forming a rectangle and a hole threaded to 30 engage the threaded end of said tubular element screwed on said threaded end and sealed thereto by sweating in a position such that one of the sides of the collar substantially engages said plane wall surface to prevent said tubular element 35 from turning when a torque is applied thereto.

4. In combination, a container, a cover for said container, a tubular element mounted within said container and extending longitudinally adjacent to one wall thereof, and a collar having external 40 sides forming a rectangle secured to said tubular element in such a position that one of said external sides engages said wall and another of said external sides is substantially flush with the top of said container so that when said cover is disposed on the container said side engages said cover. 45

WILLIAM E. SCHMIDT.
